[57] CLAIM

The ornamental design for an combined video tape recorder
and camera, as shown and described.

DESCRIPTION

FIG. 1 is a front, top and right side perspective view of an
combined video tape recorder and camera showing our new
design;

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a left side elevational view thereof;

FIG. 8 is a rear perspective view in condition that the camera
part is detached from fixational part; and,

FIG. 9 is a front perspective view in condition that the
camera part is rotated forward.
